UNITED STATES PATENT OFFICE.

ROBERT J. DAVIDSON, OF HILLBURN, NEW YORK.

DOUBLE-LOCKING SWITCH-STAND.

1,056,888.

Specification of Letters Patent. Patented Mar. 25, 1913.

Application filed December 13, 1911. Serial No. 665,498.

To all whom it may concern:

Be it known that I, ROBERT J. DAVIDSON, a citizen of the United States, residing at Hillburn, Rockland county, New York, have 5 invented certain new and useful Improvements in Double-Locking Switch-Stands, of which the following is a specification.

The invention relates particularly to switch stands that are manually operated 10 only as distinguished from switch stands of the automatic type.

The primary object of the invention is to provide means for securing switch points by a double lock so that the points cannot be 15 come loose through the failure of the mechanism connecting the switch stand to the switch points.

A further object of the invention is to provide means whereby the safety device 20 will be automatically engaged and disengaged by the operation of the switch stand.

Another object of the invention is to provide means whereby the operating handle of the switch stand cannot be lowered or se- 25 cured in its normal, non-operative position unless the switch is completely thrown.

The various other objects of the invention will be more fully set forth in the following 30 description of an apparatus embodying my invention, which consists in the new and novel features of construction and combinations of parts hereinafter set forth and claimed.

In the accompanying drawings: Figure 35 1 represents a plan view of a switch stand embodying my improved double locking mechanism. Fig. 2 represents a side elevation of the safety member showing the same attached to the switch points and showing 40 the track rails in cross section. Fig. 3 is a side elevation of a switch stand embodying 45 my improvements showing the handle in its non-operative position. Fig. 4 is a corresponding view showing the handle in its operative position. Fig. 5 is a detailed view of a portion of the switch stand and safety locking device.

The switch stand comprises a base or casing 1, the locking block 2 and the handle 3 50 operatively connected with the locking block whereby the spindle 4 may be actuated. The spindle is operatively connected with the switch points 5 by suitable means, as the connecting rod 6. The switch stand is 55 placed at the side of the track adjacent to

the switch points and operates the same in the usual manner.

Secured to the switch points preferably at or near the extreme end thereof is a connecting rod 7, which is operatively connected with a preferably curved safety plate 8, which is mounted to slide to and fro in a stationary track or guide 9 secured to or formed integral with a base 10, which may be fastened to the cross ties 11 adjacent to 60 the switch stand or in any other suitable position. The safety plate 8 is preferably secured to the connecting rod 7 by a bolt and eye connection 12, or in any other suitable manner, which will permit necessary adjustment of the safety plate to be made. The connecting rod 7 is also preferably formed in two parts adjustably secured to each other in order to provide for desirable adjustments between the switch points. 75

The base 10 provides a bearing for a locking pin 15, which is mounted to reciprocate in a line preferably transverse to the safety member. The forward end of the pin passes through a passage or opening 14 formed in 80 the guide 9. The pin is preferably made integral with a plate 16 movably mounted in a guide 17 formed integral with the base.

In order to reciprocate the locking pin 15, a connecting rod 18 is operatively connected thereto which is also secured to a lever 19 pivoted as at 19^a to the base of the switch stand. Said lever is actuated by means of a rod 20 operatively connected with the locking block so that the locking pin will be retracted when the locking block is in its 85 raised position and permit the switch to be thrown and so that the locking pin will be forced into its advanced or locking position when the locking block is in its normal or locking position. 90

Preferably, the locking block is provided with an annular flange 21 and the connecting rod 20 is provided with a slotted head 22 engaging with the locking block but permitting independent rotation thereof. A guide stud or collar 23 is secured or formed integral with the base or casing, which forms a bearing for the rod and also prevents disengagement thereof from the flange 100 on the locking block. The safety locking member 8 is provided in the portion thereof which slides in the guide 9 with the perforations 24 of sufficient diameter to permit the passage of the locking pin 15 there- 105 110

through. Said perforations are arranged apart a distance corresponding to the normal throw of the switch points so that one of said openings will register with the opening or passage 14 whenever the switch points are in their operative position. If desired, a shunt box 25 may be arranged adjacent to the safety locking plate and operated by movement of the safety member therein.

In operation, the switch points are normally secured by a double lock provided by the locking block and also by the pin which engages through one of the perforations in the safety plate secured to the switch points independently of the connecting rod that is attached to the spindle and the locking block. The disengagement of the locking block from the casing for the purpose of operating the switch will automatically retract the safety pin, however, and thus release the safety plate and permit the switch to be thrown. In case the switch receives its full throw, one of the perforations in the safety plate will be brought into register with the pin, thus permitting the switch handle and locking block to be lowered into their locked position; but in case the switch does not receive its full throw so that it comes into proper relation with the track rails, neither of the perforations in the safety plate will come into register and, consequently the safety pin cannot be operated, which will prevent the switch handle or the safety block from being lowered into their normal or locked positions. By means of this construction, a single handle may be utilized to operate both the switch spindle and locking block and also the safety device. At the same time the safety lock is entirely independent, so far as holding the switch points in proper position is concerned, of breakage or injury to the connecting rod which is secured to the switch stand spindle.

The mechanism is extremely compact, comprises comparatively few parts, and permits considerable adjustment of the parts with respect to each other.

Although I have shown one form of mechanism embodying the invention, it is obvious that various changes and modifications within the skill of the mechanic may be made in the details thereof without departing from the spirit of the invention, provided the means set forth in the following claims be employed.

I claim as my invention:

1. In a double locking switch stand, the combination with a switch stand, comprising a stationary casing, a locking block interlocking with said casing, and a handle operatively connected with the switch points and said locking block, of a safety member secured to and actuated by the switch points, means to lock said safety member in the

switch's operative position and members carried by the locking block in operative connection with last mentioned means.

2. In a double locking switch stand, the combination with a switch stand comprising a handle operatively connected with the switch points and means for locking the handle in its adjusted position, of a safety member independently secured to and actuated by the switch points, and means positively operated through said handle adapted to interlock with said safety member in the switch's operative position and to prevent the locking of said handle when the switch points are in non-operative position with respect to the stock rails.

3. In a double locking switch stand, the combination with a switch stand comprising a stationary part and a manually actuated movable part operatively connected with the switch points, of a safety device comprising a member secured to and movable with the switch points and means positively actuated by said movable part of said switch stand to lock said member.

4. In a double locking switch stand, the combination with a switch stand, comprising a stationary casing, a locking block interlocking with said casing and provided with an annular flange, a spindle secured to the switch points and a handle for releasing said locking block and rotating the spindle to operate the switch points, of a safety member secured to and actuated by the switch points, means adapted to interlock with said safety member and hold the switch points against movement, and means operatively secured to said flange for actuating said locking means.

5. In a double locking switch stand, the combination with a switch stand comprising a stationary part and a locking block operatively connected with the switch points, of a safety device comprising a member secured to and reciprocated by the switch points, a locking pin adapted to interlock with the safety member when the switch points are in their operative positions, and means positively actuated by the locking block for releasing said safety pin.

6. In a double locking switch stand, the combination with a switch stand comprising a stationary member and a manually operated switch actuating member, of a safety device comprising a safety member secured to and reciprocated by the switch points, a locking member adapted to engage with said safety member and hold same against movement, and means positively operated by and connected with said switch actuating part to engage and disengage said locking member from the safety member.

7. In a double locking switch stand, the combination with a switch stand comprising a casing, a spindle secured to the switch points, a locking block having vertical move-

ment on the spindle and interlocking with the casing, and a handle for releasing said locking block and rotate the spindle to throw the switch points, of a safety device 5 comprising a safety member secured to and reciprocated by the switch points and having perforations therethrough, a locking pin mounted transversely to the safety member and adapted to engage the perforations provided therein, and means comprising a connecting rod secured to the locking block and adapted to actuate said locking pin when the locking block is moved in a vertical plane. 10 8. In a double locking switch stand, the 15 combination with a switch stand comprising a casing, a spindle secured to the switch points, a locking block normally interlocking with the casing and having vertical movement on the spindle and rotatable therewith, and a handle adapted to move said locking block in a vertical plane and rotate the spindle to throw the switch points, of a safety device comprising a safety member secured to and reciprocated by the switch 20 25 points, and a locking pin adapted to engage with said safety member and hold same and the switch points against movement, and means for actuating said safety pin comprising a lever pivoted to the casing and a

connecting rod secured to said lever and to 30 the safety block whereby the lever is actuated when the safety block is moved in a vertical plane, said connecting rod being provided with a slotted head to permit independent rotation of the safety block, sub- 35 stantially as described.

9. In a double locking switch stand, the combination with a switch stand comprising a spindle operatively secured to the switch points, a locking block normally interlocking 40 with the casing to hold the spindle against rotation and having movement in one direction independently of the spindle, and means for releasing the locking block, of a safety device comprising a member secured to the switch points and moved therewith, a locking member adapted to interlock 45 with said safety member, and means for automatically releasing the locking member when the locking block is disengaged from 50 the casing.

This specification signed and witnessed this 6th day of December A. D., 1911.

ROBERT J. DAVIDSON.
